OF NEW YORK, N. Y.

FRICITION DRAFT AND BUFFING GEAR.

1,283,101.

Specification of Letters Patent.

Patented Oct. 29, 1918.

Application filed May 25, 1917. Serial No. 170,994.

To all whom it may concern:

Be it known that I, DONALD C. DAVIS, a citizen of the United States, residing at Buffalo, in the county of Erie and State of New York, have invented a new and useful Improvement in Friction Draft and Buffing Gears, of which the following is a specification.

This invention relates more particularly to friction draft and buffing devices for pivoted couplers of the kind which are used on railway locomotives and tenders. The invention is not, however, necessarily restricted in application to this type of coupler.

Draft and buffing devices of this kind as heretofore made do not have sufficient capacity to cushion or absorb the severe shocks to which they would be subjected if used in connection with the larger modern locomotives, such for example as the triple articulated type, which have approximately three times the tractive effort of the ordinary locomotive used in freight service. As these locomotives are commonly used in pushing service, it will be apparent that the draft and buffing devices used therewith must have a buffing capacity much greater than devices of this kind heretofore made.

The objects of the invention are to provide a combined friction draft and buffing device which has adequate capacity to cushion the draft or pulling stresses to which it is subjected, and has sufficient additional buffing capacity to cushion or absorb the severe shocks to which the device is subjected when used in connection with the larger modern locomotives; also to provide a device of this kind of compact form adapted to be arranged in the buffer or pilot beam of a locomotive or end sill of a tender or railway car; also to improve the construction of devices of this kind in other respects hereinafter specified.

In the accompanying drawings:

Figure 1 is a fragmentary top plan view of a pilot beam or end sill and friction draft and buffing device embodying the invention, the beam or sill being partly broken away to show the draft and buffing device.

Fig. 2 is a longitudinal sectional elevation thereof on line 2—2, Fig. 1, showing the coupler shank and yoke in elevation.

Fig. 3 is a transverse sectional elevation thereof on line 3—3, Fig. 1.

Briefly stated, the draft and buffing de-

vice shown in the drawings includes two friction elements which are arranged in a suitable housing or drawbar chamber preferably formed in a hollow end sill or beam and adapted to cushion the shocks transmitted to the coupler, which is also supported on the end sill or pilot beam. One of the friction elements resists strains due to both buffing and pulling and both of the elements cooperate in resisting shocks due to buffing, the device having greater capacity in buffing than in pulling.

A represents a hollow metal beam or sill adapted to be used on a locomotive, tender or piece of rolling stock, and which is provided with a drawbar chamber *a* and a plurality of chambers or pockets, in which the parts of the friction draft and buffing device are arranged. The drawbar chamber is preferably formed as shown in the lower middle portion of the hollow end sill. The sill or beam shown in the drawings is provided with a forward enlargement or projecting portion *a'* having an opening *a*² through which the shank of the coupler extends into the drawbar chamber, and the sill or beam is provided with a rearwardly extending portion *a*³.

B represents a coupler which may be of any usual or suitable type and which preferably has a short shank *b* which enters the opening *a*² in the sill or beam and is connected by means of a pivot pin *b'* to a yoke *C* which is slidably arranged in the drawbar chamber of the sill or beam, thus permitting the coupler head to swing sidewise and to move lengthwise of the locomotive or tender. By means of this arrangement the swinging movement of the coupler is limited by the side walls of the opening *a*². In the construction shown, the pivot pin *b'* may be secured in place by inserting the same through a hole *b*² in the top wall of the sill or beam into the pivot holes in the coupler shank and the yoke *C*, the hole *b*² being preferably closed by means of a suitable removable cap *b*³. A hole *b*⁴ is provided in the bottom wall of the sill or beam through which a tool may be passed for driving the pivot pin upwardly through the opening *b*². Any other suitable means for pivotally connecting the coupler shank with the yoke *C* may be employed.

The inner end of the coupler shank bears against a wedge *D* which extends transversely through the yoke *C* and is slideable

lengthwise in the drawbar chamber *a*. This wedge is provided at its opposite sides with oblique faces *d* which converge inwardly. The outward movement of the wedge *D* in the drawbar chamber is limited by means of shoulders or stop portions *d'* formed on the sill or beam. The contacting faces of the wedge and coupler shank are preferably curved concentrically with the pivotal connection between the coupler shank and the yoke *C* so as to permit the swinging or pivotal movement of the coupler. The oblique faces of the wedge *D* bear against corresponding oblique faces *e* of two oppositely disposed friction blocks *E* *E*, which are arranged in the drawbar chamber at opposite sides of the wedge *D*. The friction blocks *E* bear at their inner faces against a plate or follower *F* arranged transversely in the buffer chamber and bearing at its inner or rear face against shoulders *f* which are preferably formed integrally with the sill or beam. The yoke *C* passes around the follower *F* so that when the coupler is subjected to a draft or pulling strain, the follower *F* will move forwardly with the yoke *C*. The friction blocks *E* *E* are pressed against the oblique faces of the wedge *D* by spring plates or leaf springs *G* arranged at opposite sides of the drawbar chamber in pockets *g* formed in the sill or beam. Any number of leaf springs may be employed and they may be arranged in sets as desired to produce the required resistance to the lateral movement of the friction blocks *E*. The springs shown are arranged in three groups or sets at each side and are adapted to offer a resistance of approximately two hundred thousand pounds to the movement of the coupler in either direction.

When the coupler is subjected to buffing or pushing strains, the shank *b* will push the wedge *D* rearwardly and spread the friction blocks *E* against the action of the leaf springs *G*. When the coupler receives pulling or drawing strains, the yoke *C* draws the follower *F* outwardly or forwardly, which moves the friction blocks *E* forwardly against the oblique faces *d* of the wedge *D*, causing the friction blocks to move laterally against the action of the springs *G*, the wedge *D* in this case being held against forward movement by the stops or shoulders *d'*.

The rear or inner face of the yoke *C* bears against a second wedge *H* arranged in the drawbar chamber and provided at its sides with oblique faces *h* which bear against corresponding faces *i* of friction blocks *I*. The wedge *H* is held against forward or outward movement in the drawbar chamber by means of the shoulders or inwardly extending projections *f* of the sill or beam. The friction blocks *I* are pressed against the wedge *H* by means of spring plates or leaf

springs *K* arranged in pockets *k* formed in the sill or beam at the sides of the drawbar chamber. Any desired number of springs may be employed and the springs may be arranged in sets or groups as desired, those shown in the drawings being adapted to offer a resistance of approximately six hundred thousand pounds to the inward movement of the wedge *H*. The rear friction element constituted by the wedge *H*, the friction blocks *I* and the leaf springs *K*, resists the movement of the coupler in buffing only, and in the buffing action of the device this resistance is added to the resistance of the front friction element constituted by the wedge *D*, friction blocks *E* and springs *G*. The combined resistance of these two friction elements is sufficient to withstand the buffing action of the heaviest locomotives now used and by employing the outer friction element only to resist the drawing or pulling strains, which are much less than the buffing strains, a good cushioning effect is produced in drawing as well as a sufficiently high capacity to cushion the buffing shocks. Any suitable provision may be made for inserting the springs *G* and *K* into the pockets *g* and *k*. In the construction shown the pockets *g* and *k* are provided with openings *L* in their bottom walls which are of sufficient size to permit the spring leaves to be inserted into the pockets. The pockets are closed by means of plates *l* held in place by bolts *l'* extending through the end sill or pilot beam and passing through holes in the plates *l*. The other parts of the gear can be readily assembled through the drawbar opening in the front of the beam or sill.

The draft and buffing device described has the advantage of having sufficient capacity to cushion the heaviest buffing shocks and at the same time offering a much smaller resistance to the drawing or pulling efforts. The device is so constructed as to enable the same to be housed within the end sill or pilot beam of a locomotive, or similar beam, without unduly increasing the transverse dimensions of the sill or beam.

I claim as my invention:

1. The combination of a metal end sill having a chamber in the middle portion thereof, two wedges arranged one in front of the other crosswise of the sill in said chamber, a coupler arranged at the front of said sill to move the front wedge rearwardly, a member arranged to move the rear wedge when the coupler is moved rearwardly and to permit forward movement of the coupler independently of the rear wedge, friction means in said chamber coöperating with the front wedge to yieldingly resist both forward and rearward movement of the coupler, and supplemental friction means in said chamber coöperating with the

rear wedge to yieldingly resist rearward movement of the coupler.

2. The combination of a hollow member having a drawbar chamber, a member movable in said drawbar chamber, a coupler pivotally mounted on said movable member, two sets of friction resistance devices arranged one in advance of the other in said drawbar chamber laterally with regard to 10 said movable member, and connections between said movable member and said friction devices for causing both sets of friction devices to resist the movement of said movable member in one direction and for causing 15 one set of friction devices to resist the movement of the movable member in the other direction.
3. The combination of a metal end sill having a chamber in the middle portion 20 thereof, two wedges arranged one in front of the other crosswise of the sill in said chamber, a coupler arranged in front of said front wedge to move the wedge rearwardly, a yoke connected to the coupler and 25 passing between said wedges for pushing the rear wedge when the coupler is moved rearwardly, friction means in said chamber cooperating with the front wedge to yieldingly resist both forward and rearward 30 movement of the coupler, and supplemental friction means in said chamber cooperating with the rear wedge to yieldingly resist rearward movement of the coupler.

4. The combination of a hollow member 35 having a drawbar chamber, a member movable in said drawbar chamber, a coupler pivotally mounted on said movable member, two sets of friction resistance devices arranged one in advance of the other in said 40 drawbar chamber laterally with regard to said movable member and each including a wedge, friction blocks engaging said wedge, and means for yieldingly opposing the

movement of said friction blocks, said coupler and movable member being adapted to force said wedges against said blocks when moving in one direction, and means engaging the friction blocks of one of said sets of friction devices for moving said blocks relatively to the wedge when said movable member moves in the other direction. 50

5. The combination of a hollow member having a drawbar chamber, a coupler having a shank movable into said chamber, two sets of friction resistance devices arranged 55 in said drawbar chamber laterally with respect to said shank, and connections between said shank and said sets of resistance devices for transmitting the movement of the coupler in buffing to both sets of said 60 devices, and for transmitting the movement of the coupler in pulling to only one set of said devices.

6. The combination of a hollow member having a drawbar chamber, a yoke movable 65 in said chamber, a coupler pivotally connected to said yoke, two sets of friction devices arranged in said member, each including a wedge, friction blocks engaging said wedge, and springs resisting the movement 70 of said blocks by the wedge, said yoke and coupler actuating said wedges when the coupler moves in one direction to cause a shock to be transmitted to both sets of said friction devices, and means for moving the 75 friction blocks of one of said friction devices relatively to the wedge of said friction device when the coupler is moved in the opposite direction.

Witness my hand, this 22nd day of May, 80
1917.
